CLAIM

The ornamental design for an electric shoe polisher, as shown and described.

DESCRIPTION

FIG. 1 is a perspective view of an electric shoe polisher showing our new design;

FIG. 2 is another perspective view thereof;

FIG. 3 is a front elevation view thereof;

FIG. 4 is a back elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is a perspective view of the electric shoe polisher in a state of use.

The broken lines depict portions of the electric shoe polisher that form no part of the claimed design.

1 Claim, 9 Drawing Sheets
